UNITED STATES PATENT OFFICE.

CLYDE J. COLEMAN, OF NEW YORK, N. Y.

FUEL-BURNING APPARATUS.

1,024,925.

Specification of Letters Patent.

Patented Apr. 30, 1912.

Application filed April 18, 1907. Serial No. 368,910.

To all whom it may concern:

Be it known that I, CLYDE J. COLEMAN, a citizen of the United States, residing at the borough of Manhattan, in the county of New York and State of New York, have invented a certain new and useful Improvement in Fuel-Burning Apparatus, of which the following is a specification, reference being had therein to the accompanying drawings, forming a part thereof.

My invention relates to wick lamps and is an improvement on my former patented invention, United States Patent No. 796,899, dated August 8, 1905.

15 The object of my present invention is to secure simplified construction, increased efficiency of operation and additional convenience of maintenance.

My invention comprises improved means 20 for supplying fuel to a circular or other endless wick and improved means for rotating or driving the wick relatively to the seat of combustion to vary the point of ignition of the wick.

25 My invention also includes a circular wick removable (for renewal or cleaning) from the outside of the fuel receptacle and without disturbing any mechanism therein.

My invention also includes means for rendering 30 the wick-feeding mechanism operative when the liquid fuel is at extremes of high or low level.

My invention also includes various improvements in the construction and combination 35 of parts, and has other objects and advantageous features, as will appear from the following description.

I will now describe the embodiment of my invention illustrated in the accompanying 40 drawings, after which I will point out my invention in claims.

Figure 1 is an elevation, partly in section, of a railway signal lamp embodying my improvement, the lamp being shown partially in middle section. As shown in this figure the fuel-oil of the lamp is nearly all consumed. Fig. 2 is an enlarged vertical transverse central sectional elevation of the lamp exclusive of the casing or lamp box, and 45 with the flue or chimney omitted, and shows the lamp as almost completely filled with fuel-oil. Fig. 3 is a transverse central sectional elevation as viewed from the left of Fig. 2. Fig. 4 is a greatly enlarged trans- 50 verse or diametrical sectional elevation of

the wick holder and circular or disk-shaped wick shown in the preceding figures. Figs. 5, 6 and 7 are similar views showing modified forms of wick holders and wicks.

The lamp illustrated comprises a sheet-metal fuel receptacle or oil tank 1, the body portion of which may be formed in one piece as shown and the top or cover of which is shown as fixedly secured in usual manner to the body portion. The tank is provided 60 with an ordinary filling-tap 2. The means for bringing the fuel oil to the seat of combustion include a flat circular or disk-shaped wick 3 which may be of felt or other suitable wick material. The wick is removably 65 clamped between similar or duplicate wick-clamping disks or plates 4 by a flanged screw 5 coating with a flanged nut 6 (Fig. 4), the two disks and the screw and its nut 70 constituting a wick-holder and such screw 75 and nut together also constituting a wick-spindle or arbor for the rotatable wick. The wick extends in the direction of its diameter from a point within to a point 75 without the tank and is retained in place 80 and guided by lugs or spindle-brackets 7 secured to the top of the tank and having spindle-guiding notches 8 in which the wick-spindle is rotatably and removably mounted. To more effectually inclose the lowermost 85 portion of the wick and to prevent the escape of fuel-oil by splashing, as in handling the lamp, a wick-inclosing sheath or tube 9 extends from a point flush with the top 90 of the wick-guiding lugs 7 to a point below the top of the tank surrounding the wick, but leaving the lowermost portion of the periphery of the wick downwardly exposed. The seat of combustion or ignition point of the wick is determined and restricted by a 95 burner dome 10 which removably telescopes over the lugs 7 and sheath 9 and is centrally upwardly provided with a wick slot or ignition slot 11, the wick being ignited where it is exposed at the wick slot. The 100 wick 3 is comparatively narrow or thin and the width of the flame extends circumferentially of the wick, as seen in Fig. 1. To better promote combustion and to cool the adjacent parts, such parts comprising the 105 burner dome 10 and the wick-clamping disks 4, the burner dome is provided at each side with a plurality (shown as four at each side, eight in all) of small draft openings or ventilating apertures 12. Peripheral 110

breaks or radial slots 13 are provided in the disks 4, to retard the conduction of heat in the disks 4, away from the point of ignition. The burner dome 10 is shown as provided 5 with four radial chimney-supporting arms or flue-retaining brackets 14 for supporting and holding in place a usual and ordinary flue or chimney 15 (Fig. 1). To clean the wick 3 or to replace it with a fresh wick the 10 burner dome 10 is lifted off and the wick and wick-holder removed by lifting out of the guide-slots 8.

Improved means are provided for supplying fuel-oil to the wick and for automatically rotating the wick to present fresh 15 points of the wick at the seat of combustion. In the construction illustrated fuel-oil is supplied to the lowermost portion of the periphery of the wick and from thence is 20 conveyed to the point of ignition by capillarity. The means for supplying fuel-oil to the wick 3 comprise a circular feed-wick shown as a flat wick 16 encircling and supported by a wick-drum or wick-carrier 17 25 carried in turn by a spindle or axle 18 which is rotatably mounted and supported by drum-supporting brackets 19 depending from the cover of the tank 1. The drum axle 18 is parallel to the spindle, 5 and 6, of the wick 30 holder and is preferably, as shown, located in the same vertical plane. The drum 17 is supported at the proper height so that the ignition-wick 3 is in contact with and rests upon the uppermost portion of the feed-wick 16 and with the wick-holder-spindle 35 above the bottom of the slots 8, as shown, thus assuring perfect continuity of contact between the two wicks. The feed-wick 16 is of considerable width and wider than the 40 ignition-wick 3 to provide an ample and easy capillary path for the fuel-oil on its way to the wick 3. Also for the same purpose and to increase the extent of the capillary path a supplemental feed-wick 20 is 45 provided diametrical to the drum 17 and forming an additional and shorter fuel-path when the fuel-oil reaches a low level (Fig. 1). The feed-wicks 16 and 20 may consist of usual flat wick material. The drum 17 is 50 of the proper diameter to enable the feed-wicks to take up the fuel-oil from near the bottom of the tank.

Automatic means are provided which are actuated commensurately to fuel consumption 55 to rotate the ignition-wick 3 to vary the point of ignition. Such means comprise a two-part wick-feeding float 21 carried by the drum 17 near its periphery, the drum 17 thus being a wick-feeding drum. 60 The floats may be composed of cork with a suitable impervious coating. To secure adequate buoyancy in the space available and to avoid corners which might become wedged against the inner walls of the tank, the 65 floats 21 are of cylindrical contour. These

cylindrical floats are axially supported by a shaft or spindle 22 carried by and passing through the drum 17 at a point near its edge or periphery. To provide free space for the floats in their uppermost positions, the drum 70 supporting brackets 19 are hollowed out or bent as shown. As the wicks 3 and 16 have rolling contact with each other, it is evident that any movement of the floats 21 will be communicated through the drum 17 and 75 feed-wick 16 to the wick 3 and will rotate the wick 3 and present a new point thereof at the ignition slot 11. The floats 21, as the fuel oil in the tank is consumed, will descend through an arc determined by the 80 drum 17, effecting the above-described rotation of the drum and circumferential or peripheral shifting of the wick 3. The amplitude of arcuate movement of the wick-feed- 85 drum 17 and the feed-wick 16 is determined by the distance of rise and fall of the wick-feeding floats 21 and is arranged to be such as to about cause one complete revolution of the ignition-wick 3. Before any considerable portion of the fuel-oil has been 90 consumed the positions of the various parts will be as appears in Fig. 2, and after such fuel-oil has been mostly consumed the positions will be as appears in Fig. 1.

To enable the wick-actuating or wick- 95 feeding mechanism to be operative at times when the fuel-oil in the tank is at a higher or at a lower level than would otherwise be possible with the floats 21 alone, a counter-weight 23 is provided to supplement or assist the action of the floats. Such counter-weight is located near the periphery of the drum 17 and on a different radius or at a point angularly displaced from the floats 21. The location of the counterweight is 100 such that when the floats are in the upper part of their path the counterweight and floats will be on the same side of a vertical plane passing through the axis of the drum 17; and when the floats are in the lower part 105 of their path, the counterweight and floats will be on opposite sides of such vertical plane. When the counterweight is in the first-named position (Fig. 2) it acts in opposition to the floats and causes greater submergence of the floats, thus enabling the floats to be operative to actuate the work at a higher fuel level, as the floats are kept out of contact with the top or cover of the fuel tank at such higher level, due to the increased submergence of the floats. When the counterweight is in the last-named position (Fig. 1) it acts by its weight to lift the floats and produces less submergence of the floats and thus renders the floats operative 110 with a less quantity of fuel-oil contained in the tank. The final result is that the floats 21 move a less vertical distance than the difference in liquid levels through which they are operative to feed or actuate the wick 3, 115 120 125 130

but such restricted or decreased movement of the floats communicates an increased or multiplied movement to the wick 3, to the necessary extent by reason of the relation of 5 the larger drum 17 to the smaller wick 3 so that the wick 3 is rotated substantially through one revolution between the extremes of float movement.

The lamp as illustrated is provided with 10 a usual outer casing or lamp box 24 (Fig. 1) having a vertical socket or pocket by which it is shown as hung or detachably supported on one leg of a U-shaped bracket 25 the other leg of which is secured to a suitable 15 support 26 which may be considered as representing a portion of a signal post.

In the modified construction of ignition-wick illustrated in Fig. 5 the wick 27, corresponding in circular outline and function 20 to the wick 3, is not removable from its holder, but may be cleaned therein and used over again if desired, and finally the wick and holder may be discarded together. In this construction the wick is held or clamped 25 between plates or disks 28 which are retained in position by a tube or large eyelet 29 riveted or upset over the plates as shown, and a wick-spindle 30 is tightly driven through the tube 29. The disks 28 30 are provided with heat-stopping or heat-retarding slots 31 like the slots 13.

The construction shown in Fig. 6 resembles that of Fig. 4 in that the wick is removable from its holder, but differs in that 35 the complete wick holder consists of two parts only. The wick 32 is clamped between wick-holding disks 33 and 34 having coacting screw threads and spindle-ends formed integral therewith respectively as 40 shown. Slots 35 are provided corresponding to the slots 13.

In the construction illustrated in Fig. 7 an annular cord wick 36 is shown as employed and is sprung into a peripheral 45 groove in a wick-carrying core or disk 37 having a central aperture through which is forced a wick-spindle 38, such core and spindle constituting a wick-carrier. The wick 36 may be renewed in reference to the 50 wick-carrier.

In all of the modified constructions of wick and wick-holders the operation when in the lamp is the same and the same as in the case of the wick 3, and any of the wick-holders illustrated in Figs. 4, 5, 6 and 7 together with its wick could be exchanged or substituted for each other in the lamp construction shown.

It is obvious that various modifications 60 may be made in the constructions shown and above particularly described within the principle and scope of my invention.

I claim:

1. A wick-lamp comprising a source of 65 liquid fuel, a rotatable circular wick ex-

posed to the seat of combustion at a rotating part thereof, and automatic means actuated commensurately to fuel consumption for rotating the wick relative to the seat of combustion to vary the point of ignition, such means including a circular device having a 70 rolling contact with the wick for supplying fuel thereto.

2. A wick lamp comprising a source of liquid fuel, a rotatable circular wick exposed to the seat of combustion at a peripheral point of ignition, and automatic means actuated commensurately to fuel consumption for rotating the wick relative to the seat of combustion to vary the point of ignition, such means including a circular device having rolling contact with the wick for supplying fuel thereto. 75

3. A wick lamp comprising a rotatable circular wick exposed to the seat of combustion at a rotating part thereof, fuel-supplying means for the wick having rolling frictional contact therewith for supplying fuel to the wick and for communicating rotation to the wick for shifting the wick relative to the seat of combustion to vary the point of ignition, a source of liquid fuel and automatic means actuated commensurately to fuel consumption for actuating the fuel-supplying means, and thereby rotating the 90 wick. 95

4. A wick lamp comprising a rotatable circular wick exposed to the seat of combustion at a peripheral point of ignition, fuel-supplying means for the wick having rolling frictional contact therewith for supplying fuel to the wick and for communicating rotation to the wick for shifting the wick relative to the seat of combustion to vary the point of ignition, a source of liquid fuel, and automatic means actuated commensurately to fuel consumption for actuating the fuel-supplying means, and thereby rotating the 100 wick. 105

5. Fuel-burning apparatus comprising a 110 source of liquid fuel, a rotatable circular ignition-wick having a rotating point of ignition, a rotatable circular feed-wick having peripheral frictional driving contact with the ignition-wick, and automatic means actuated commensurately to fuel consumption to rotate the feed-wick and thereby rotate the ignition-wick to circumferentially vary the point of ignition. 115

6. Fuel-burning apparatus comprising a 120 source of liquid fuel, a rotatable circular ignition-wick on which is the base of the flame at a peripheral point of ignition, a rotatable circular feed-wick in communication with the source of liquid fuel and in 125 frictional driving engagement with and having capillary continuity with the ignition-wick, and a float buoyed by the liquid fuel and coöperating with the feed-wick to rotate the feed-wick and thereby rotate the 130

ignition-wick and draw its periphery continuously through the base of the flame.

7. Fuel-burning apparatus comprising a source of liquid fuel, a rotatable circular ignition-wick having a rotating point of ignition, an endless feed-wick having frictional driving contact with the ignition wick, and automatic means actuated commensurately to fuel consumption to actuate the feed-wick and thereby rotate the ignition-wick to circumferentially vary the point of ignition.

8. Fuel-burning apparatus comprising a source of liquid fuel, a rotatable circular ignition-wick on which is the base of the flame at a peripheral point of ignition, an endless feed-wick in communication with the source of liquid fuel and in frictional driving engagement with and having capillary continuity with the ignition-wick, and a float buoyed by the liquid fuel and co-operating with the feed-wick to actuate the feed-wick and thereby rotate the ignition-wick and draw its periphery continuously through the base of the flame.

9. Fuel-burning apparatus comprising a source of liquid fuel, an endless ignition wick having a limited point of ignition, an endless feed-wick having frictional actuating contact with the ignition-wick, and automatic means actuated commensurately to fuel consumption to actuate the feed-wick and thereby actuate the ignition-wick to shift the point of ignition thereupon.

35 10. Fuel-burning apparatus comprising a source of liquid fuel, an endless ignition-wick on which is the base of the flame at a restricted point of ignition, an endless feed-wick in communication with the source of liquid fuel and in frictional actuating engagement with and having capillary continuity with the ignition-wick, and a float buoyed by the liquid fuel and co-operating with the feed-wick to actuate the feed-wick and thereby actuate the ignition-wick and draw it continuously through the base of the flame.

11. Fuel-burning apparatus comprising a receptacle for liquid fuel, a rotatable feed-wick within the receptacle, a float buoyed by the liquid fuel and adapted to rotate the feed-wick, and a rotatable circular ignition-wick having a rotating point of ignition and adapted to be rotated by the feed-wick to shift the point of ignition, the ignition wick having capillary continuity with the feed-wick and being so mounted as to be freely removable from the outside of the receptacle.

60 12. Fuel-burning apparatus comprising a receptacle for liquid fuel, a rotatable feed-wick within the receptacle, a float buoyed by the liquid fuel and adapted to rotate the feed-wick, and a rotatable circular ignition-wick having a rotating point of ignition and

resting upon the feed-wick and adapted to be rotated thereby to shift the point of ignition and being so mounted as to be freely removable from the outside of the receptacle.

13. Fuel-burning apparatus comprising a receptacle for liquid fuel, a rotatable ignition-wick, a rotatable feed-wick adapted to rotate the ignition-wick and having capillary continuity therewith, a float buoyed by the liquid fuel and adapted to rotate the feed-wick, and a counterweight acting to depress the float in the upper position of the latter and acting to elevate the float in the lower position of the latter, whereby the float is operative at extremes of fuel level the distance between which is greater than the total extent of vertical travel of the float.

14. A wick-lamp comprising a source of liquid fuel, wick-moving means including a fuel-buoyed controlling-float, and means for rendering the controlling-float operative at extremes of fuel level the distance between which is greater than the total extent of vertical travel of the float.

90 15. Fuel-burning apparatus comprising a receptacle for liquid fuel, a rotatable ignition-wick, a rotatable feed-wick adapted to rotate the ignition-wick and having capillary continuity therewith, a pivoted wick-carrier for the feed-wick, a wick-actuating float mounted on the wick carrier eccentrically to its pivot and buoyed by the liquid fuel, to rotate the wick-carrier and thereby rotate the ignition-wick, and a counterweight mounted on the wick-carrier at an eccentric point thereon on a different radius from the float and so that in the lower position of the float the counterweight and float are at opposite sides of a vertical plane passing through the axis of the wick-carrier and so that in the upper position of the float the counterweight and float are at the same side of such vertical plane.

16. A wick-lamp comprising a receptacle for liquid fuel, a rotatable ignition-wick, a rotatable annular feed-wick adapted to communicate rotation to the ignition-wick and having capillary continuity therewith, a wick-drum upon the periphery of which the annular feed-wick is mounted, means actuated by the lowering of the fuel level in the receptacle for rotating the wick-drum, and a supplemental feed-wick carried by the wick-drum and providing a shorter capillary path for the fuel to the ignition-wick when the fuel is at a low level in the receptacle.

110 17. Fuel-burning apparatus comprising a source of liquid fuel, an endless ignition-wick having a limited point of ignition, a rotatable circular feed-wick having peripheral frictional driving contact with the ignition wick, and automatic means actuated commensurately to fuel consumption to ro-

tate the feed-wick and thereby actuate the ignition-wick to shift the point of ignition thereupon.

18. Fuel-burning apparatus comprising a source of liquid fuel, an endless ignition-wick on which is the base of the flame at a restricted point of ignition, a rotatable circular feed-wick in communication with the source of liquid fuel and in frictional driving engagement with and having capillary continuity with the ignition-wick, and a float buoyed by the liquid fuel and coöperating with the feed-wick to rotate the feed-wick and thereby actuate the ignition-wick and draw it continuously through the base of the flame.

19. A wick-lamp comprising a source of liquid fuel, wick-moving means including a fuel-buoyed controlling float, and means acting to depress the float in the upper position of the latter and acting to elevate the float in the lower position of the latter.

20. A wick-lamp comprising a source of liquid fuel, wick-moving means including a fuel-buoyed controlling float, and a counterweight acting to depress the float in the upper position of the latter and acting to ele-

vate the float in the lower position of the latter.

21. A wick-lamp comprising a receptacle for liquid fuel, a rotatable ignition-wick, a rotatable annular feed-wick adapted to communicate rotation to the ignition-wick and having capillary continuity therewith, a wick-drum upon the periphery of which the annular feed-wick is mounted, and means actuated by the lowering of the fuel level in the receptacle for rotating the wick-drum.

22. Fuel-burning apparatus comprising a source of liquid fuel, an endless wick having a limited point of ignition, and automatic means actuated commensurately to fuel consumption for shifting the point of ignition on the wick, such means including a circular device having a rolling contact with the wick for supplying fuel thereto.

In testimony whereof I have affixed my signature in presence of two witnesses.

CLYDE J. COLEMAN.
